ABSTRACT

The control system is for a punch press having a reciprocatable bolster plate, and requires that run buttons of the system be depressed and held in place in order to energize first and second relays which control a bolster-in solenoid for a bolster-in actuating means. The energization of the bolster-in solenoid causes the bolster-in actuating means to move the bolster plate from a load position at the front of the press to a work position at the rear of the press. The bolster plate, as it nears the rear of the press, trips a first limit switch completing a holding circuit for the first relay and, upon arriving at the rear of the press, trips a second limit switch to deenergize the bolster-in solenoid. Both run buttons must be released simultaneously in order to energize a third relay and a ram solenoid thereby causing reciprocation of a ram. A third limit switch responsive to the cycling of the ram deenergizes the first, second and third relays at the conclusion of each cycle. Contacts of the first and third relays, operative upon deenergization, close and thus complete a circuit to the bolster-out solenoid thereby causing the bolster-out actuating means to move the bolster plate to the load position.

CONTROL SYSTEM FOR A PUNCH PRESS

BACKGROUND OF THE INVENTION

The present invention relates to a control system for a metal forming press of the type having a bolster that moves from a loading area to a work area prior to operation of a ram of the press, and more particularly to such a system including means to insure that the operator's hands are outside the work area when the ram descends.

The concept of requiring an operator of a metal forming press to maintain two push buttons depressed while the press is operating is not new. Such systems increase safety because both of the operator's hands must be held on the respective push buttons during operation of the press and the buttons are located remote from the work area. Physical harm upon accidental or inadvertent "tripping" of the associated press ram is thereby avoided. Such systems, however, are easily defeated by short circuiting or wedging down one of the push buttons so that only one hand is needed to depress the remaining push button thereby to activate the press. A hazard arises because the operator may then place his other hand into the press and receive physical injury as a result of the press ram coming down unexpectedly. The foregoing has been true of conventional presses as well as those that provide for loading of a press outside of the work area.

SUMMARY OF THE INVENTION

According to the present invention there is provided an improved control system for a punch press having a reciprocatable bolster plate and ram. The system comprises a plurality of push buttons, electromagnetic relays, and limit switches which control solenoids which control movement of the movable parts of the press.

Upon depressing two run buttons of the system, first and second electromagnetic relays are energized. Energization of the first relay opens contacts in a bolster-out circuit and closes contacts in a bolster-in circuit. A bolster-in solenoid is thus energized thereby causing operation of a bolster-in actuating means.

As the bolster moves inwardly from a load to a work position, release of either one or both of the run buttons causes deenergization of the bolster-in solenoid and the energization of a bolster-out solenoid thereby to reverse the direction of movement of the bolster and thus return it to the load position. If both of the run buttons remain depressed, the bolster continues its inward movement to the work position and trips a first limit switch as it nears its work position which completes a holding circuit for the first relay.

When the bolster plate arrives at its work position, it trips a second limit switch which deenergizes the bolster-in solenoid thereby stopping the inward movement of the bolster. At this point in the cycle, a circuit to a ram solenoid which controls the tripping of the press ram automatically becomes energized if both run buttons are released simultaneously or within a limited interval of time from each other. If release of the second run button is delayed for a predetermined time, the second relay opens a contact in the ram solenoid circuit thereby precluding operation of the ram actuating means and closes another contact in the bolster-out solenoid circuit causing the bolster to move outwardly to the load position.

If both run buttons are released simultaneously or within a short time of each other, a third relay is energized before the second relay operates. A by-pass contact of the third relay then locks in the ram solenoid circuit thereby causing operation of the ram actuating means before the second relay drops out. A third limit switch is responsive to cycling of the ram actuating means and deenergizes the first, second and third relays after each cycle. Normally closed contacts of the first, second and third relays then cause energization of a circuit to the bolster-out solenoid causing the bolster-out actuating means to move the bolster outwardly to the load position.

It is an object of this invention to provide an improved control system for a punch press which requires that both hands of an operator depress respective run buttons in order to initiate and continue operation of the press.

It is a further object of this invention to provide an improved control system including means to preclude the short circuiting or wedging down of one of two run buttons in an attempt to operate the press with only one run button.

BRIEF DESCRIPTION OF THE DRAWINGS

Other objects and advantages of the invention will become apparent from the following detailed description wherein reference is made to the accompanying drawings, in which:

FIG. 1 is a side elevation view of a punch press of the type to which this invention can be applied; and

FIG. 2 is a schematic wiring diagram illustrating a preferred embodiment of the invention.

DETAILED DESCRIPTION OF THE INVENTION

Referring to the drawings, the control system includes four limit switches 11, 12, 13 and 14, a pair of push buttons 21 and 22, and three electromagnetic relays 31, 32 and 33. The relays 31, 32 and 33 are represented schematically in FIG. 2 by operating windings 31w, 32w and 33w, respectively, and the contacts 31a to 31d; 32a and 32b; and 33a to 33c, respectively. The limit switches and push buttons are shown in FIG. 1 as mounted on a punch press 34 and are shown schematically in the wiring diagram of FIG. 2.

Referring now more particularly to FIG. 2, power for the control system is supplied from a suitable source indicated by conductors L1 and L2. The limit switch 11 has a normally closed contact 11a, and the limit switch 12 has two normally open contacts 12a and 12b and two normally closed contacts 12c and 12d. The limit switch 13 has a normally open contact 13a and a normally closed contact 13b, and the limit switch 14 has a normally open contact 14a and a normally closed contact 14b. The push button 21 has a normally open contact 21a and a normally closed contact 21b, and the push button 22 has a normally open contact 22a and a normally closed contact 22b. The relay 31 has three normally open contacts 31a, 31b and 31c and a normally closed contacts 31d; the relay 32 has a normally open contact 32a and a normally closed contact 32b; and the relay 33 has two normally open contacts 33a, and 33b and a normally closed contact 33c.

To provide for a time delay in the drop out of the relay 32, a diode 35 is in series with the winding 32w and a capacitor 36 is in parallel with the winding 32w.

The control system is designed for use with a punch press of the general type shown in Ferris et al. U.S. Pat. No. 3,446,106 issued May 27, 1969 to which reference may be had for a complete description. Referring to FIG. 1, a ram 38 of the punch press 34 is reciprocated by a drive mechanism including a fly wheel 41 driven by a motor 42. The ram carries the upper portion of a die (not shown) which cooperates with a lower die (not shown) on a bolster plate 44. The bolster plate 44 is moved inwardly and outwardly by a hydraulic actuating means controlled by a four-way detent valve (not shown), which is operated by a pair of solenoids 45 and 46 having windings 45w and 46w (FIG. 2), respectively.

As described more completely in the Ferris et al. patent, the limit switch 12 is operated by the bolster 44 as it moves inwardly and nears the work position, and the limit switches 13 and 14 are operated by the bolster when it reaches its innermost or work position. A clutch (not shown) associated with the fly wheel 41 is controlled by a hydraulic valve (not shown), which is operated by a solenoid 47 having a winding 47w. Energization of the solenoid 47 causes the clutch to engage the rotating fly wheel 41 which in turn reciprocates the ram 38 through one cycle.

Normal and proper operation of the control system will now be described. With the ram 38 at the top of its stroke, the limit switch 11 is closed, and the bolster plate 44 is in its outer or load position because the bolster-out solenoid 46 is energized through the circuit from the conductor L1, the contacts 11a, a conductor L1', the contacts 31d, a junction 50, the contacts 33c and the winding 46w to the conductor L2.

Depression of the push buttons 21 and 22 causes energization of the winding 31w from the conductor L1' through the contacts 21a, 22a, and 12d, a junction 52 and the winding 31w to the conductor L2, and causes energization of the winding 32w from the conductor L1' through the contacts 21a, 22a, 12c, a junction 54, the diode 35 and the winding 32w to the conductor L2. Opening of the contacts 31d upon energization of the winding 31w effects deenergization of the bolster-out solenoid 46, and closure of the contacts 31a effects energization of the bolster-in solenoid 45 by a circuit from the junction 54 through the contacts 13b, 14b, and 31a and the winding 45w to the conductor L2 thus causing the bolster plate 44 to move inwardly toward the work position. The contacts 31b and 31c also close, as do the contacts 32a, but they perform no function at this time. Opening of the contacts 32b also is without result.

When the bolster plate 44 is a short distance from its full-in or work position, the bolster plate contacts an arm of the limit switch 12. The initial movement of the arm results in the closing of contact 12a and the opening of contact 12c. The closing of contact 12a completes a holding circuit for the winding 31w through the now closed contacts 31c and 12a and the junction 52. As the arm of the switch 12 is moved further by the bolster plate, contact 12d opens and contact 12b closes. The opening of contact 12d interrupts the circuit to the winding 31w through the contacts 21a and 22b and thereby eliminates any possibility of current flow from the junction 52 to the junction 54. The contact 12b closes so that the junction 54 remains connected to the conductor L1' through the contacts 21a and 22a.

Upon the bolster plate 44 reaching the work position, the limit switches 13 and 14 trip. Tripping of the limit switches 13 and 14 opens the contacts 13b and 14b and closes the contacts 13a and 14a. Opening of the contacts 13b and 14b interrupts the energizing circuit for the bolster-in solenoid 45, but the closure of the contacts 13a and 14b completes no circuit so long as the push buttons 21 and 22 remain depressed.

Normally, both of the push buttons 21 and 22 are released simultaneously shortly after the bolster plate 44 reaches the position where limit switch 12 is actuated. Assuming such a simultaneous release, the contacts 21a and 22b both open together and the contacts 21b and 22b both close together. Opening of the contacts 21a and 22b causes de-energization of the winding 32w after a brief time delay effected by the diode 35 and the capacitor 36. Before the relay 32 drops out thereby opening its contact 32a and closing its contact 32b, the winding 33w is energized from the conductor L1' through the now-closed contacts 21b, 22b, 32a, and 31b and the winding 33w to the conductor L2. The relay 33 picks up and is held in that position against the opening of the contacts 32a by closure of its contacts 33b which are connected directly in parallel with the contacts 32a. The opening of the contacts 33c interrupts a circuit to the bolster-out solenoid winding 46w to insure that the bolster plate 44 does not move out of the work position at this time. Upon pick-up of the relay 33, the contacts 33a also close to complete an energizing circuit for the clutch solenoid winding 47w from the conductor L1' through the contacts 21b, 22b, 33b, 31b, 13a, 14a, and 33a and the winding 47w to the conductor L2. Energization of the clutch solenoid 47 causes the press ram 38 to start a cycle.

As soon as the ram 38 starts its cycle, the contacts 11a open to effect de-energization of the relays 31 and 33. When the ram 38 again reaches the top of its stroke, the contacts 11a close and complete the circuit through the now-closed contacts 31d and 33c to the winding 46w of the bolster-out solenoid 46 causing the bolster plate 44 to move outward to the load position for unloading and reloading preparatory to another cycle.

It sometimes happens that an operator releases one or both of the push buttons 21 and 22 too soon and before operation of the limit switch 12. In this case, the winding 31w is immediately de-energized and always before the ram 38 starts its cycle. Consequent drop-out of the relay 31 causes closing of the contacts 31d to energize the bolster-out solenoid 46 and the bolster plate 44 returns to the load position. The cycle then has to be initiated again by closure of both run buttons 21 and 22.

If the push buttons 21 and 22 are released non-simultaneously after operation of the limit switches 12, 13 and 14, release of the first one causes the relay 32 to start timing out. If the relay 32 drops out before the other run button is released, the release of the other button causes the winding 46w of the bolster-out solenoid 46 to be energized through the contacts 21b, 22b, 32b and 33c and the bolster plate 44 moves out to the load position.

Thus it is apparent that there has been provided, in accordance with the invention, a control system for a punch press that fully satisfies the objects, aim, and advantages set forth above. While the invention has been described in conjunction with specific embodiments

thereof, it is evident that many alternatives, modifications, and variations will be apparent to those skilled in the art in light of the foregoing description. Accordingly, it is intended to embrace all such alternatives, modifications, and variations as fall within the spirit and broad scope of the appended claims.

I claim:

1. A punch press control system wherein a pair of push buttons must both be depressed to complete a first electric circuit which, when completed, causes operation of means for moving a bolster plate of the punch press from a loading to a work position, limit switch means responsive to the bolster plate reaching the work position partially completes a second electric circuit which, when completed, causes operation of a means for effecting reciprocation of a ram of the punch press through one cycle, and release of both push buttons completes the second circuit, said system being characterized in that time delay means are provided to prevent completion of the second circuit if the release of one of the push buttons is delayed beyond a predetermined time after release of the other push button.

2. A punch press control system as claimed in claim 1 wherein the system includes a relay having a coil in a circuit energized concurrently with the first circuit and a normally open contact in the second circuit, said contact closing upon energization of the coil, said coil being associated with the time delay means thereby to delay deenergization of the relay coil upon opening of the first circuit.

3. A punch press central system as claimed in claim 2 wherein the time delay means includes a diode and a capacitor connected in series and parallel, respectively, with the coil.

4. In a control system for a punch press of the type having a bolster plate reciprocatable between a loading position and work position and a ram reciprocatable through a cycle from a first to a second relatively displaced position and back to the first position, said control system comprising: first, second and third electromagnetic relays each having an energizing circuit; a bolster-in solenoid having an energizing circuit and operative when energized to cause the bolster plate to move from the loading position to the work position; a bolster-out solenoid having an energizing circuit and

operative when energized to cause the bolster plate to move from the work position to the loading position; a ram solenoid having an energizing circuit and operative when energized to cause the ram to reciprocate through said cycle; a pair of depressible and releasable push buttons each having a normally open and a normally closed contact, the normally open contacts of the push buttons being connected in series with each other in a circuit forming part of the energizing circuits for the first and second relays and the bolster-in solenoid, the energizing circuits for the first and second relays being completed upon closure of the normally open contacts of both push buttons when the bolster plate is in the loading position; a normally open contact of the first relay in the energizing circuit for the bolster-in solenoid which contact when closed completes the energizing circuit for the bolster-in solenoid through the normally open contact of the push buttons when those contacts are closed and the bolster plate is not in the work position; the normally closed contacts of the push buttons being connected in series with each other in a circuit forming part of the energizing circuits for the third relay and the ram and bolster-out solenoids; a normally open contact of each of the first and second relays being connected in series with each other in a circuit forming part of the energizing circuits of the ram solenoid and the third relay; a normally open contact of the third relay being interposed in the energizing circuit for the ram solenoid; the energizing circuit for the third relay being completed when the normally closed contacts of the push buttons are closed and the first and second relays are energized and the energizing circuit for the ram solenoid being completed upon energization of the third relay; normally closed of the second and third relays being in series with each other in the energizing circuit for the bolster-out solenoid and in series with the normally closed contacts of the push buttons, the improvement which comprise means to provide a time interval in the drop-out of the second relay so that both push buttons must be released simultaneously or within a predetermined time of each other to open their normally open contacts and to close their normally closed contacts thereby to cause energization on the ram-solenoid.
